UNITED STATES PATENT OFFICE.

ARTHUR F. POOLE, OF KENILWORTH, ILLINOIS, ASSIGNOR TO REMINGTON ACCOUNTING MACHINE CORPORATION, OF NEW YORK, N. Y., A CORPORATION OF NEW YORK.

CALCULATING MACHINE.

Application filed February 16, 1922. Serial No. 536,960.

To all whom it may concern:

Be it known that I, ARTHUR F. POOLE, citizen of the United States, and resident of Kenilworth, in the county of Cook and State of Illinois, have invented certain new and useful Improvements in Calculating Machines, of which the following is a specification.

My invention relates to calculating machines and it has for its principal object to provide certain improvements in clearance proof mechanism for such machines. I have shown my invention applied to a combined typewriting and calculating machine in which the totalizers are cleared by setting the actuators for subtraction and copying the total by operating the numeral keys. In machines of this character, the totalizer will always come to zero provided the total has been correctly copied.

My invention has for one of its principal objects to provide improved means for notifying the operator in case a predetermined one of a plurality of totalizers has not been cleared at the time when it should have been. Another object of my invention is to provide in addition to a lock other means of notifying the operator that a totalizer is not cleared, namely, a visual indicator. In the particular machine shown in the drawings there are a plurality of these indicators, one for each of the totalizers whose clearance is to be proven, so that in case the lock has been operated to notify the operator that a totalizer is not clear the appropriate one of these indicators will show which totalizer it is that should have been cleared and has not.

To the above and other ends my invention consists in certain features of construction and combinations and arrangements of parts, all of which will be fully set forth herein and particularly pointed out in the claims.

One instance of my invention is illustrated in the accompanying drawings which show said invention applied to a Remington accounting machine which, except as hereinafter described, may be constructed in accordance with the patent to John C. Wahl for calculating machines, No. 1,349,024, patented August 10, 1920. In said drawings—

Figure 1 is a conventional front elevation of so much of said machine as is necessary to

illustrate the application of my invention thereto.

Figure 2 is a similar view but on a larger scale and more in detail and omitting some of the parts shown in Fig. 1. In Fig. 2 however the two vertical totalizers shown are not adjusted to the same relative positions on the truck as in Fig. 1.

Figure 3 is an isometric view of part of my mechanism.

Figure 4 is a fragmentary top plan view.

Figure 5 is an isometric view of parts of my mechanism.

Figure 6 is a view in vertical section about on the line 6—6 of Fig. 4.

Figure 7 is a side elevation of one of the cross footing totalizers and some of the associated parts, the side plate of said totalizer being broken away to show some of the interior mechanism.

One form of the Remington accounting machine including a single cross footing totalizer in combination with a plurality of vertical totalizers, is shown and described in the patent to John C. Wahl, No. 1,270,471 for calculating machines, patented June 25, 1918. The machine shown in the Patent No. 1,349,024 above referred to, is an extension of that shown in No. 1,270,471 to provide for a plurality of cross footing totalizers in place of the single cross footing totalizer of the earlier patent. From these two patents together the construction of the machine to which my improvements are here shown applied, can be fully understood.

The Remington accounting machine includes a Remington typewriter which is not shown in detail in the present drawing but which includes printing keys 10, types 11 operated by said keys, and a platen 12 mounted in a carriage and on which the paper is placed. The principal frame piece 13 of the Wahl calculating mechanism is a long casting 13 secured by certain brackets to the top plate 14 of the typewriter, Fig. 4. Running on certain wheels 9 carried by the frame piece 13 at the middle of the machine is a main totalizer truck 15, Fig. 2, which is connected at its ends to the typewriter carriage to travel in unison therewith. I have shown seven totalizers, 1, 2, 3, 4, 5, 6 and 7, mounted on this truck to calculate numbers written in seven columns

on the paper. These totalizers are operated in the well-known manner by a master wheel, not shown, but which is part of the actuator mechanism which is operated by 5 the numeral keys 10 of the typewriter.

Two cross totalizers 23 and 24 are mounted on a cross truck 25 in position to be operated, the first by a master wheel 26, and the other by a master wheel 27, which master 10 wheels are operated and controlled in the manner described in the Patent No. 1,349,024 above referred to. Said truck 25 runs by ball bearings on rails 28 secured at their ends to frame plates 30 and 31 which frame 15 plates are secured to the main frame bar 13. The truck 25 is intermittently drawn toward the left by means of a hook 32 which is caught up by one after another of the vertical totalizers and is released at the end 20 of each adding column; and said truck when released is drawn back to its right-hand position shown in Fig. 1 by means of a spring 33. When so drawn back it is arrested by a bar 34 on the truck striking 25 against a lever 35 pivoted at 36 to the frame plate 31 and pressing said lever flat against said frame plate 31, as shown in Fig. 1. The lever 35 is normally held by 30 a spring 37 a short distance to the left of plate 31 as shown in Figure 2. The lever 35 has connected thereto a slide bar or link 38 which at its left-hand end is articulated with a bell crank 40 which is one of the controlling devices of a certain lock which lock 35 is fully described in the Wahl patents hereinbefore referred to.

Said lock is also controlled in part by a certain roller 41, Fig. 6, which is normally pressed upward by a spring but 40 which, when one of the vertical totalizers is brought by the travel of the carriage into a calculating zone over its master wheel, is depressed by a trackway 42 constituting part of the framework of said totalizer. 45 The construction of the lock is such that whenever one of the vertical totalizers 1-7 is over the main master wheel, and when therefore the roller 41 is depressed and if at that time the cross truck has not been 50 hooked up to said totalizer, as it should be, but stands in its right-hand position as shown in Fig. 1, then the keys of the machine will be locked against operation; but under other conditions this lock will be ineffective. 55 The lock is operated by the joint action of the roller 41 and the lever 35, and is effective when said roller is depressed and said lever is in its right-hand position. This lock is thus particularly mentioned be- 60 cause in the present instance I use it in my clearance proof mechanism, but I have not illustrated the lock in detail partly because its construction is well-known and partly because any other suitable locking means 65 can be employed instead. I use this one

because it happens to be in the machine and is convenient for my purpose.

The master wheels 26 and 27 are each capable of being rotated in one direction for addition and in the reverse direction for 70 subtraction, and in the Wahl machine said wheels are thus controlled by certain change gear mechanism which in turn can be controlled by a variety of means described in the Wahl patents above cited. One of said 75 means consists of an automatic control, part of which is shown in the drawing. As shown in Figs. 1, 2 and 6, each of the vertical totalizers has two cam plates, a front 80 plate 43 and a rear plate 44, said plates secured to the framework of the totalizer by a screw 45 and other means fully described in Patent No. 1,349,024. The plate 43 controls a follower roller 46 and the plate 44 a follower roller 47, said rollers being pressed 85 upward by springs and being depressed on occasion by the respective cam plates. The roller 46 is connected to the change-gear mechanism which controls the master wheel 26 for the cross totalizer 23. The roller 47 90 is connected with the change gear which controls the master wheel 27 for the cross totalizer 24. The construction is such that when one of these rollers is in its highest 95 position the corresponding master wheel will be rotated for addition; when said roller is in its lowest position said master wheel will be rotated reversely for subtraction and when said roller is in an intermediate or middle position said master wheel 100 will be disconnected so as not to be turned when the keys are operated. The plates 43 and 44 have provision for adjustment to the several positions described, as fully set forth in Patent No. 1,349,024.

By way of illustration, the machine is shown in Fig. 1 set up preparatory to computing an account in the following form:

1.	2.	3.	4.	5.	6.	7.	110
Debits.		Credits.		Total debits.	Total credits.	Balances.	115
Labor.	Material.	Cash.	Contra account.				
1.23	4.56	1.15	5.27	36.63	19.12	17.51	
7.89	9.87	3.74	8.96				
7.65	5.43	.....	.....	.....	.....	.....	

In this account column "1" contains various debit items of labor, column "2" debit items of material, column "3" credit items in cash, and column "4" credit items by contra account. Column "5" contains the total debits, this being the sum of all the items in columns "1" and "2". Column 120 "6" contains the total credits which is the sum of all the items in columns "3" and "4". Column "7" contains the balances which consist of the difference between the amounts in columns "5" and "6". The ma- 130

chine is set up so that the various columns are added respectively in the vertical totalizers 1, 2, 3, 4, 5, 6 and 7. The various cams 43 and 44 are so set or adjusted that at the same time all items in columns "1" and "2" are added in cross totalizer 23 and all items in columns "3" and "4" are added in cross totalizer 24. The totals indicated on these cross totalizers are copied respectively in columns "5" and "6". In order to get the balance for column "7" the machine is so set that when writing column "5", that is the total debits, neither of the cross totalizers is operated, the amount written in column "6" is subtracted from both cross totalizers; and the amount written in column "7" is subtracted from totalizer 23. As the amount written in column "6" is the amount that was indicated in totalizer 24, the act of writing column "6" should clear that totalizer and at the same time the total credits will be subtracted from the amount indicated on totalizer 23. Said totalizer 23 will then show the difference between the total credits and the total debits. This difference is then copied in column "7" and subtracted from totalizer 23. In order to carry out this scheme of addition and subtraction the cam plates 43 and 44 on the several totalizers 16-22 have been set as indicated in Fig. 1. When one of these cams is set in its highest position it causes addition in the corresponding one of the two totalizers and when the cam is set in its middle position it causes the corresponding totalizer to be disconnected. For example, on each of totalizers 1 and 2 the front cam 43 is set up for addition and the rear cam 44 is set in its middle position for disconnect so as to cause amounts added on these two registers to be added on the cross totalizer 23 and not be registered at all in totalizer 24. In columns "3" and "4" this relation is reversed, whereas in column "5" both cams are set at disconnect position. In column "6" both are at subtract and in column "7" 43 is at subtract and 44 at disconnect.

It will be perceived that if the work is correctly done totalizer 24 will come to zero at the end of the writing of column "6" and totalizer 23 will come to zero at the end of the writing of column "7". I have therefore provided means for notifying the operator in case the totalizer 23 is not clear at the end of column "6" and in case totalizer 24 is not clear at the end of column "7". This example is given merely by way of illustration. The clearance test could be made to take place at any other point desired in the program of operation by a simple adjustment of the vertical totalizers, as will hereinafter appear.

My clearance proof mechanism includes

means for automatically locking the keys 65 immediately after the writing of the last digit in any computing column where it is desired to test for clearance. In the present instance the mechanism is set to lock the keys at the ends of columns "6" and 70 "7". Said clearance proof mechanism also includes means whereby in case the particular totalizer is clear which it is desired to test at that particular time, then the lock will immediately be released, but if that 75 totalizer is not clear the lock will continue in action. In the present instance the mechanism is shown set so that immediately after writing the last digit in column "6" 80 the keys will be locked by means which are not affected by totalizer 23 but if totalizer 24 is then clear it will, during its jump-back to the right at the end of column "6", release the lock. In the same way at the end of column "7" totalizer 23 if clear will 85 release the lock.

The means for locking the keys comprises means for operating the lever 35 so as to press said lever to its locking position independently of the truck 25, so that therefore even if said truck is properly hooked up to write a number the keys will be found locked. A frame plate 50 is secured to the casting 13 by means of screws 51 in such fashion that it extends parallel to said casting and behind it as shown in Fig. 4. A post 52 in the nature of a pivot screw is screwed into this frame plate and it has pivoted thereon two three-armed levers 53 and 54 best shown in Fig. 3. Each of said levers has one of its arms extending downward and terminating in a lug 55 which lies in front of the locking lever 35 in such positions that if either of the levers 53 or 54 were swung toward the right from the position shown in Fig. 2 it will operate said lever 35 to lock the keys. Said levers are normally held in their inactive positions shown in Fig. 2 by means of two latch levers 56 and 57 pivoted on a pivot stud 58 projecting forward from the plate 50. Each of said latch levers has a horizontally extending arm having at its end a notch in which normally rests a lug 60 bent off from the upper end of one of the levers 53, 54. A spring 61 is connected to each lever 53 or 54 above its pivot and to the corresponding latch lever beneath the pivot of the latter and this spring performs the double function of holding the latch lever in latching position and of moving the lock lever 53, 54 to locking position when released from its latch. Each of the levers 56 and 57 has an upstanding arm in position to be operated, the first by a push wire 62 and the last by a push wire 63, these wires passing through suitable holes in an ear 64 bent off from the plate 50 and standing with their

ends in such position that if one of them be moved toward the right it will release the corresponding latch lever.

Near the middle of the machine a sheet metal bracket 65 is secured to the top of the casting 13 by means of screws 66 and this bracket is bent first upward and then forward to produce an overhanging portion to which is secured a pivot screw 67 here shown as provided with a lock nut 68. This screw hangs downward and is headed at its lower end and it has pivoted thereon two bell cranks 70 and 71, the former above the latter as shown. Each of these bell cranks is made of sheet metal with a double bend in it so as to give it two points of pivotal bearing on the screw or post 67. Each of said bell cranks has the lower plane thereof extending rearward through a suitable opening in the bracket 65 so as to constitute a rearwardly extending arm of the bell crank and the push wire 62 is pivoted to the upper one of these arms and the push wire 63 to the lower one. Each of the bell cranks has its upper level or plane prolonged toward the left to constitute the other arm of the lever and to these arms, dogs 72 and 73 are pivoted at 74. Each of said dogs is connected behind its pivot to a spring 75 tending to rock the dog about its pivot and the rocking of said dog by said spring is limited by a pin 76 projecting upward from said dog and striking against the lever arm. Each lever is controlled as a whole by a tension spring 77 tending to rock the levers counter-clockwise as seen from above.

The dogs 72 and 73 project forward from their respective levers 70 and 71 and each of said dogs has its left-hand face made abrupt and its right-hand face made inclined and said dogs are adapted to be operated by means of two tappets 78 and 80. The tappet 78 consists of the upper end of a bracket 81, Figs. 2, 4 and 6, secured as by screws 82 to the top of the totalizer 7. Said bracket extends from said totalizer toward the right and upward and the tappet 78 consists of a rearward projection of said bracket adapted to engage the dog 72 but not to engage the dog 73, as the carriage travels back and forth. The tappet 80 consists of a like rearward projection from a bracket 83 similarly secured to the totalizer 6 and similarly formed except that it projects only high enough to engage the dog 73. The parts are shown in Fig. 4 in the position they occupy when the operator is about to strike a key to write the last digit in column "7" corresponding to totalizer 7. Tappet 78 is in such position with relation to the inclined edge of dog 72 that during that step of the carriage immediately following the writing of said last digit said tappet will act on said dog tending to rock it clockwise in Fig. 4. As the dog is prevented by the pin 76 from rock-

ing in that direction about its own pivot 74 it will rock the lever 70 clockwise and push the wire 62 toward the right, thus releasing latch lever 56 and allowing locking lever 53 to drop to locking position, that is to say, in such position as to press locking lever 35 back to its locking position. The tappet 78 during the same step of the carriage, passes dog 72 and allows lever 70 to return immediately to normal position. In the same way locking lever 54 will be released by tappet 80 acting momentarily on dog 73 at the end of the adding column controlled by totalizer 6. When the carriage is drawn back toward the right the tappets 78 and 80 engage the abrupt left-hand faces of the dogs and rock said dogs about their pivots 74 and against the tension of their springs 75 until each tappet escapes from its dog when the dogs will immediately be restored to normal position. The levers 70 and 71 are therefore not operated when the carriage is moved toward the right but are operated when it is moved toward the left.

It will be perceived that the lock can be thrown in at any desired position in the travel of the carriage by suitably locating the totalizers 6 and 7, and that in setting up the machine for any particular piece of work one of these totalizers, or another similarly equipped, could be set wherever it was desired to test the clearance of one or the other of the cross totalizers 23 and 24.

When the machine is locked at the end of the sixth column, by the means that have just been described, it is immediately thereafter unlocked by means in the cross totalizer 24, provided said cross totalizer is clear at the time, as it should be; and when the machine is locked at the end of column "7" it is similarly unlocked by means included in the totalizer 23. The means included within the cross totalizers 23 and 24, for thus unlocking the machine in case the appropriate totalizer is clear, is substantially identical with that shown and described and claimed in my prior application for Letters Patent, Sr. No. 462,628, filed Apr. 19, 1921, and said means is sufficiently well shown for the purposes of the present application in Figs. 2 and 7 of the drawings. Each of said totalizers is, with certain exceptions to be presently pointed out, of the ordinary construction of Wahl totalizers, including certain carrying gears 84 which transmit motion by means of idlers, not shown, to the pinions 85 of the dial wheels 86, said pinions and wheels being rotatably mounted on a shaft 87 in the totalizer. Each of said pinions 85 has one shortened tooth 88 which, when the dial wheel 86 shows a "0" through the sight-opening, stands in the position shown in Fig. 7 where it co-operates with one tooth of a feeler comb 90, which comb is pivoted at 91 in the side plates of the

totalizer. This comb 90 includes a series of thin teeth or blades which pass between the dial wheels 86 in the planes of the pinions 85. When any one, or more, of said pinions has one of its ordinary long teeth presented to the comb 90 said comb is held in its rearmost position, but when all of the dials are lined up in their zero positions so that every one of the pinions 85 presents a short tooth to the comb 90, then said comb can rock toward the front of the machine to the position shown in Fig. 7. At its right-hand end this feeler comb has an arm 92 extending therefrom rearward and having a tooth 93 at its end which engages a notch in the forward end of a lever arm 94 which is pivoted on one of the cross bars 95 ordinarily present in the Wahl totalizer. The lever arm 94 is one arm of a bell crank 20 which has also an upstanding arm 96 which constitutes a trigger that projects out through the top casing plate of the totalizer which is made with a slot for the purpose. A spring 97 acting on the arm 94 tends to move the parts to the position shown in Fig. 7; that is to say, to the position they occupy when the totalizer is clear. At such time the arm 96 occupies its rearmost position but if any one of the pinions 85 be turned to bring a long tooth opposite the feeler 90, said arm or trigger 96 would be moved at its upper end toward the front of the machine.

The locking lever 54 hereinbefore referred to has an arm 100 projecting therefrom approximately horizontally toward the left and has near its left-hand end an inclined part 101, Fig. 2. The construction is such that when at the end of column "6" the lever 54 is freed, this arm 100 drops down from its normal position shown in Fig. 2 to a lower position where it operates the locking lever 35. On the same step of the carriage, however, which releases this lever the cross truck 25 is released and makes its jump toward the right. If at this time the said totalizer is clear the arm 96 will occupy its rear position shown in Fig. 7, in which position the now depressed arm 100 is directly in its path. Said arm 96 therefore encountering the incline 101, cams the lever arm 100 upward, thus restoring the lever 54 to its normal position and the latch 56 immediately locks it there. If however, the totalizer 24 is not clear at the time, the arm or trigger 96 will occupy its forward position and in its motion toward the right will move in front of the arm 100 and not engage said arm so that said arm will remain in its lower position and the machine will remain locked.

As shown in the drawing and perhaps most clearly in Fig. 3, the lever 53 has an arm 102 projecting leftward therefrom as much further than the arm 100 as the total-

izer 23 is to the left of totalizer 24. This arm 102 has an off-set part 103 to bring its free end into the same transverse vertical plane as the free end of the arm 100 and said arm 102 also has an incline 104 for the same purpose as the incline 101. The totalizer 23 is equipped with a trigger 96 and the controlling mechanism therefor precisely as in the totalizer 24, and the parts operate in the same way, except that the trigger 96 for totalizer 23 acts on the lever 102 instead of on the lever 100. It will thus be seen that there are two complete clearance proof mechanisms provided, one for each of the cross totalizers. When lever 54 is tripped off to lock the machine it will be moved to unlocking position only in case the totalizer 24 is clear, the state of the totalizer 23 having no effect on this lever; and similarly the locking lever 53 can be released only by the totalizer 23 and not by the totalizer 24. It will thus be seen that the machine can be so set up as to test for clearance, at any point in the travel of the carriage, of either of these totalizers independently of the other.

In case one of the totalizers is not clear when it should have been and the machine is thereby locked up, as soon as the operator notices that the machine is locked up and observes the cause of it the clearance proof mechanism will have performed its function. The operator can then readily release the machine by raising the depressed lever arm 100 or 102 by hand and can then proceed to correct the error in the usual way.

From what has been said it will be perceived that the lever 53, 102 constitutes what may be called a warning device to warn the operator that the totalizer is not clear, and that the lever 54, 100 is similarly a warning device for the totalizer 24.

It is desirable though not essential to provide a visual indicator to show that one or the other of the totalizers 23 and 24 was not cleared when it should have been. To this end I have constructed the lever arms 100 and 102, as best shown in Fig. 3, where it will be seen that each of them has at an appropriate place in its length been prolonged upward to make a target 105, each of which targets has a streak or red 106 thereon. The balance of the target may be of any suitable color, preferably the same color as the casing plate presently to be described, so that when the lock is not in operation this target construction is inconspicuous. Said casing consists of a plate 107, Fig. 4, spaced a short distance in front of the casting 13 to which it is secured by screws 108. This casing plate has two sight openings 110 suitably located so that when one of said targets 105 is down its red stripe 106 will show through said slot. This visual indicator is useful because adding machines con-

tain a number of locks and where the operator finds the machine locked against operation it is useful to have some such indicator or bracket as this to show at a glance what 5 the trouble is. In the present instance if a red streak shows through the left-hand slot 110 it indicates that the left-hand totalizer 23 should be clear but is not and a similar trouble with the right-hand totalizer 24 10 is indicated by a red streak showing through the right-hand slot 110. Also if the operator is alert he will see this streak even before he tries to operate the machine and finds it locked. It of course will be understood that 15 this indicating device or something equivalent can also be used in the simpler form of clearance proof mechanism shown in my prior application Sr. No. 462,628, hereinbefore referred to.

20 Each of the lever arms 100 and 102 is shown with a pin 111 projecting rearward therefrom, Figs. 2, 3, and 4, and each of said pins passes through a key-hole slot 112 in the frame plate 50. The pin has an annular groove turned therein and the enlarged part of the slot 112 is big enough to admit the full diameter of the pin but the curved part of the said slot is only large enough to admit the reduced part of the pin. This 25 construction braces the arms 100 and 102 against displacement front and back and prevents them from getting out of proper alignment for proper co-operation with the triggers 96.

30 35 In my prior application for Letters Patent, filed August 15, 1921, Sr. No. 492, 396, I have shown a clearance proof mechanism applied to the accounting machine shown and described in the aforesaid Wahl 40 patent, No. 1,349,024 and adapted to test for clearance the two cross-footers shown in said patent, one of them at one point and the other at another point of the carriage travel; and said prior application contains claims 45 broad enough to read on the construction of the present application. By my present construction, unlike that shown in my said prior application, the act of proving clearance of one totalizer is independent of that of proving clearance for the other totalizer so that 50 by present construction it is possible by suitably arranging the two tappets 78 and 80 to prove the clearance for both totalizers at once in case such a thing is desirable.

55 This would preferably be done by mounting both tappets on one bracket. Moreover, my present construction is not limited in its application to two totalizers. I have shown means for proving clearance of two totalizers 60 but it is obvious that the scheme can be extended to a large number which could not be so readily done in the construction shown in my earlier application. Moreover, the present construction is simpler and better 65 mechanically than my prior construction.

In short, the present construction is an advance in several respects over that shown in my said prior application.

Various changes may be made in the details of construction and arrangement without departing from my invention.

What I claim as new and desire to secure by Letters Patent, is:—

1. In a calculating machine, the combination with a traveling carriage, a plurality of totalizers and means for operating said totalizers, of a plurality of tappets on said carriage and traveling in different paths, a plurality of locking devices one thrown into action by each of said tappets of a predetermined position of said carriage, and means in each of said totalizers for restoring one of said locking devices in case a totalizer is clear.

2. In a calculating machine, the combination with a traveling carriage, a plurality of totalizers and means for operating said totalizers, of a plurality of locking devices one associated with each of said totalizers, means for automatically actuating one of said locking devices at one point in the travel of the carriage and another of said locking devices at another point in the travel of the carriage, and means in one of said totalizers for restoring one of said locking devices in case that totalizer is clear, and means in another totalizer for restoring another of said locking devices in case said other totalizer is clear.

3. In a calculating machine, the combination with a traveling carriage, a plurality of cross totalizers each capable of registering numbers in a plurality of zones of carriage travel, of a locking device associated with each of said totalizers, means in each totalizer for restoring its associated locking device in case said totalizer is clear, and means on said carriage for causing one of said locking devices to be actuated at one point of carriage travel and another of said locking devices to be actuated at another point of said carriage travel.

4. In a calculating machine, the combination with a traveling carriage, a series of columnar totalizers and a series of cross totalizers each capable of registering numbers which numbers are also registered distributively in said vertical totalizers, of a plurality of non-clearance warning devices one associated with each of said cross totalizers, means associated with certain of said vertical totalizers to trip said devices to non-clear position at different column positions of said carriage, and means in each of said cross totalizers to restore its associated warning device in case said cross totalizer is clear.

5. In a calculating machine, the combination with a traveling carriage, a plurality of cross totalizers and means for operating

said cross totalizers, of a plurality of warning devices one associated with each of said cross totalizers, a plurality of levers adjacent said carriage and one above another, 5 a plurality of tappets on said carriage, one adapted for each of said levers, means connecting said levers with the respective warning devices to actuate the same to indicate non-clear at predetermined positions of the 10 carriage travel, and means in each of said cross totalizers immediately to restore its associate warning device in case said cross totalizer is clear.

6. In a combined typewriting and calculating machine, the combination with a typewriting carriage, a series of vertical totalizers and a plurality of cross totalizers, of a plurality of warning devices one associated with each of said cross totalizers, 15 means associated with certain of said vertical totalizers to move said warning devices to indicate non-clear at certain zone positions determined by the travel of the carriage, and means in each of said cross totalizers for restoring its associate warning device in case said cross totalizer is clear.

7. In a calculating machine, the combination with a traveling carriage and a jumping truck having two cross totalizers mounted thereon, of two warning devices mounted in stationary framework, one adjacent the path of travel of each of said cross totalizers, means for automatically dropping said devices one at a time to indicate non-clear, 30 and triggers in said cross totalizers, each trigger adapted in case that totalizer is clear to engage and restore its associate warning device.

8. In a calculating machine, the combination with a traveling carriage and a jumping cross totalizer, of a lever extending transversely of the machine adjacent the path of travel of said jumping totalizer, means for tripping said lever at predetermined times and allowing it to drop down to non-clear position, means in said totalizer for immediately restoring said lever in case 45 the totalizer is clear, and a colored target upon said lever arranged to show a spot

of color above said totalizer when said lever is in non-clear position.

9. In a calculating machine, the combination with a traveling carriage, a plurality of jumping totalizers and means for operating the same, of clearance proof mechanism for 55 said jumping totalizers including a plurality of targets mounted on the stationary framework one in the vicinity of each of the jumping totalizers, and means whereby the appropriate one of said targets displays 60 a visional indication in case one of said jumping totalizers is not clear when it should be.

10. In a calculating machine, the combination with a traveling carriage, a plurality 65 of totalizers and means for operating said totalizers, of a plurality of tappets on said carriage and traveling in different paths, a clearance testing device in each of said totalizers, and independent trains of connections extending from the respective tappets to the respective clearance testing devices.

11. In a calculating machine, the combination with a traveling carriage, a plurality 75 of cross totalizers, and means for operating said totalizers, of a plurality of independent clearance proving devices for the respective totalizers, each of said clearance proving devices being controlled independently of another such device by the 80 travel of said carriage.

12. In a calculating machine, the combination with a traveling carriage, a jumping cross-truck, a plurality of cross totalizers mounted on said truck, clearance proof 85 mechanism for each of said totalizers, and a plurality of means each independent of another, whereby said carriage controls said clearance proving mechanism.

Signed at the borough of Manhattan, city 90 of New York, in the county of New York and State of New York, this 15th day of February, A. D. 1922.

ARTHUR F. POOLE.
